UNITED STATES PATENT OFFICE.

PERLEY F. HAZEN, OF ST. JOINSBURY, VERMONT, ASSIGNOR TO THE E. & T. FAIRBANKS & COMPANY, OF SAME PLACE.

DESIGN FOR A SCALE-WEIGHT.

SPECIFICATION forming part of Design No. 33,084, dated August 14, 1900.

Application filed June 14, 1900. Serial No. 20,371. Term of patent 14 years.

To all whom it may concern:

Be it known that I, PERLEY F. HAZEN, a citizen of the United States, residing at St. Johnsbury, in the county of Caledonia and State of 5 Vermont, have invented and produced a new and original Design for a Scale-Weight, of which the following is a specification.

My invention relates to a new and original design for scale-weights; and it consists in the 10 article hereinafter described, and referred to in the appended claim.

In the drawings which illustrate the invention, Figure 1 presents a plan view of a scale-weight embodying my design, and Fig. 2 is a 15 cross-section of the same.

In the drawings, A represents the scale-weight as a whole, having the open-ended slot B and the raised central portion C, formed with a deep groove *d* around it, the weight 20 being cut away underneath, as shown at E,

and the upper walls F extending beyond the body of the central portion. From the inner end of the open-ended slot B raised curved ribs H extend to the bead F.

The essential feature of the invention consists in the weight of the shape and configuration herein shown. 25

Having thus described my invention, what I claim, and desire to secure by Letters Patent, is—

The design for a scale-weight, substantially as shown and described.

In testimony whereof I have hereunto affixed my signature in the presence of two witnesses. 30

PERLEY F. HAZEN.
